UNITED STATES PATENT OFFICE.

MATTHIAS E. VAN BROCKLEN AND RICHARD HAIDEN, OF AMSTERDAM, NEW YORK.

ROLLER-CLEANER.

1,352,852.

Specification of Letters Patent. Patented Sept. 14, 1920.

Application filed January 3, 1920. Serial No. 349,316.

To all whom it may concern:

Be it known that we, MATTHIAS E. VAN BROCKLEN and RICHARD HAIDEN, citizens of the United States, and residents of Amsterdam, in the county of Montgomery and State of New York, have invented certain new and useful Improvements in Roller Cleaners, of which the following is a specification.

10 Our invention is an improvement in roller cleaners, and has for its object to provide a device of the character specified, adapted for use with spinning mules, for cleaning the rollers of the spinning jacks, wherein the 15 arrangement is such that when the cleaner is placed upon the roller, it will travel the full length of the roller, thoroughly cleaning the same, and requiring no supervision on the part of the spinner, and it may be used upon 20 many machines.

In the drawings:

Figure 1 is a front view of the spinning jack showing the device in place,

Fig. 2 is a diagrammatic end view,

25 Fig. 3 is a section on the line 3—3 of Fig. 4,

Fig. 4 is a plan view of the motor for the cleaner,

Fig. 5 is a side view of the cleaner,

30 Fig. 6 is an end view of the same.

In the present embodiment of the invention, a motor is provided comprising a substantially channel-shaped support or carriage, consisting of a body 1 and side walls 35 2, the side walls depending from the body in spaced relation.

This plate has openings 3 on opposite sides of its center in the body thereof. In each of these openings there is mounted a 40 roller 4, each roller having journal pins 5, which are engaged in bearings 6 on the body, and the peripheral surfaces of these rollers are roughened or corrugated as shown to provide surfaces for gripping the roller to 45 be cleaned.

The axes of the two rollers are inclined in the same direction, and are parallel, and a suitable handle 7 is connected with the support, for convenience in handling the same.

50 This handle is connected at its end to the ends of the body, by means of screws 8 or the like, and a coupling lug 9 is provided at one end of the body, the adjacent end of the handle being connected with this lug.

55 The cleaner as shown in Fig. 5 comprises

a body portion 10 and wing plates 11 which are connected to the sides of the body by screws 12, and the wing plates depend well below the body. These wing plates engage the roller 13 to be cleaned, and act as cleaners thoroughly scraping the roller as the motor moves the cleaner longitudinally of the roller.

The body 10 of the cleaner has a pair of perforated ears at one end, and these ears are spaced to receive the lug 9 before mentioned. This lug has an arc shaped slot 14, and a coupling pin 15 is passed through the slot and through openings 16 in the ears. This opening permits considerable vertical movement of the pin with respect to the lug.

A guide is provided at one side of the motor, for engaging an adjacent roller to prevent overturning of the motor by the rotation of the roller 13^a to be cleaned. As shown more particularly in Fig. 2, the yarn indicated at 17 passes from the drum 18 over a drum 19 to the roller 13^a being held in close contact with the undersurface of the roller 13^a by means of rollers 20 and 21 which are arranged on opposite sides of the roller 13 and below the same.

The guide for the motor 1—2 engages the yarn at roller 21, which is in rear of the 85 roller 13^a. This guide is a T-shaped member, the stem portion 22 thereof having a longitudinally extending slot 23, and this portion 22 extends transversely of the support 1—2 between the openings 3.

The slot is engaged by a bolt 24 which adjustably connects the stem of the T-shaped guide to the body of the support. The cross head 24^a of the guide extends longitudinally of the support, and this guide 22—24 has a 95 depending portion 25 which engages the peripheral surface of the roller 21.

In operation, the motor with the cleaner attached is set on the roller 13^a to be cleaned. It will be obvious that as the roller 13^a rotates the motor will be driven longitudinally thereof, because of the peculiar arrangement of the rollers 4. As the motor moves it draws the cleaner with it, and the peripheral surface of the roller 13^a is thoroughly 105 scraped. When the motor reaches the end of the roller 13^a it will stop.

No attention to the cleaner is required on the part of the spinner, and when the cleaner has reached one end of the roller 13^a it can 110

be reversed, and will return to the other end, the element 25 now being on the other side of the support.

As soon as the motor is lifted out of contact with the roller 20 or 21, it will stop. It will be noticed that the scraping plates 11 are beveled at their free edges to form cutting edges. The cross head portion of the guide has its ends beveled in both directions, in order that it may pass along the yarn. Since the roller to be cleaned rotates toward the drum carrying the coarse yarn the tendency of the motor is to tilt toward the said drum, and the engagement of this cross head portion of the guide with the yarn prevents such tilting movement.

We claim:

1. A device of the character specified, comprising a channel-shaped support having openings in the body thereof, and rollers journaled in the openings and having their

axes inclined to the long axis of the support for the purpose specified, and a guide arm extending laterally from the support and adjustably connected therewith. 25

2. A device of the character specified, comprising a channel-shaped support having openings in the body thereof, and rollers journaled in the openings and having their axes inclined to the long axis of the support 30 for the purpose specified, and a channel-shaped cleaner pivotally connected to the motor and adapted to be drawn thereby.

3. A device of the character specified, comprising a channel-shaped support having 35 openings in the body thereof, and rollers journaled in the openings and having their axes inclined to the long axis of the support for the purpose specified.

MATTHIAS E. VAN BROCKLEN.
RICHARD HAIDEN.
